WAVE CONVERSION

Harry Tunick, Rye, N. Y., assignor to Radio Corporation of America, a corporation of Delaware

Application June 16, 1942, Serial No. 447,225

27 Claims. (Cl. 250—15)

1

My present invention relates to conversion of waves of one frequency to waves of another frequency. My invention has particular application to radio relaying systems for relaying frequency or phase modulated waves or, more generally, angle modulated waves.

Some of the objects of my invention are, to improve radio relaying circuits, to provide radio relaying circuits which are substantially free of undesired frequency drifts, and to provide radio relaying circuit arrangements highly free of distortion and in which the re-transmitted waves always bear a substantially fixed relation in frequency to the received wave or waves to be relayed.

Other objects, advantages and features of my invention will be apparent as the more detailed description thereof is given.

In the accompanying drawings:

Figure 1 illustrates a radio relaying system in which the difference frequency between received and re-transmitted waves is derived by frequency dividing the received waves. Figure 1 also employs a local source of oscillations used first, for heterodyning down the received waves and then, for heterodyning back, modified waves for retransmission.

Figure 2 is a modified form of Figure 1 in which the local heterodyning oscillator has been eliminated.

Figure 3 is another form of my invention wherein one part of the received waves is frequency divided and then combined with another part of the received waves to produce a different frequency for re-transmission, and

Figure 4 is a modified form of Figure 2.

Referring to Figure 1, ultra short waves are received upon the antenna 2 and fed through transmission line 4 to amplifier 6. The waves received upon antenna 2 are assumed to be frequency or phase modulated or, more generally, angle modulated. For greater ease in explaining the invention of Figure 1, it shall be assumed that the received waves have a mean or carrier frequency of 500 megacycles and that the carrier has been modulated with one or more signals. Further, it is assumed that the maximum frequency swing of the carrier produced by maximum amplitude signal voltages is plus and minus 200 kilocycles.

It is to be clearly understood that these frequency values have been arbitrarily chosen and are illustrative only and are not to be considered in any way as limiting the present invention.

Part of the amplified energy from amplifier 6

2

is fed through line 8 to frequency dividers and amplifiers 10 so that the output thereof as illustrated is .5 mc. in line 12. This frequency divided energy is further amplified and filtered in amplifier 14.

Another portion of the output of amplifier 6 is fed to a converter or heterodyning detector 16. Converter 16 is also supplied through transmission line 18 with heterodyning waves of a mean frequency of 600 megacycles. This 600 mc. heterodyning wave may be derived, as shown, from a relatively constant frequency oscillator 20 and frequency multiplier 22.

Of the resulting beat frequencies in the output 15 of converter 16, the difference frequency or 100 megacycles is fed through amplifier and filter 24 and thence to a second converter or heterodyning detector 26 which is also supplied with the divided energy of .5 mc. from the output of amplifier 14 through line 28.

The upper side band produced in converter 26 is then selected by amplifier and filter 30 and for the values assumed this upper side band would have a mean frequency of 100.5 megacycles. This 25 selected upper side band from amplifier and filter 30 is then fed to another converter 32 by way of line 34. Converter 32 is also supplied with 600 mc. locally generated waves through line 36. The output of converter 32 may then be fed to a filter 38 and amplifier 38 through line 40. Filter and amplifier 38 may be adjusted and constructed so as to pass the mean difference frequency or 499.5 megacycles to the re-transmitting antenna 42 by way of line 44. If desired, of course, 38 may be adjusted and constructed so as to pass the other or upper side band which would have as its mean frequency 500.5 megacycles.

Also, it is to be understood that filter 39 may be adjusted so as to pass 99.5 mc. in line 34 and in that event filter 33 could be adjusted so as to pass waves having mean frequencies of either 700.5 megacycles or 699.5 megacycles.

In the arrangement of Figure 1 certain decided advantages obtain. First, it is to be noted that 45 any changes in frequency of the local oscillator 20 prove substantially self-cancelling in the resultant output since waves derived from oscillator 20 are employed in successive heterodyning processes. Thus, if the oscillator frequency drifts, 50 the drift is first subtracted and then added in the successive heterodyning processes and, hence, the final output is left unaffected by the drift. By means of the frequency dividers 10 and converter 26 the resulting re-transmitted frequency at 42 55 is different than that received. This difference

in frequency, when either 499.5 or 500.5 mc. is re-transmitted, is equal to the frequency of the output of divider 10. Since the mean output frequency of divider 10 depends entirely upon the received wave, the re-transmitted wave at 42 always bears a definite fixed relation with respect to the received wave at 2. The arrangement of Figure 1, therefore, offers a decided advantage over installations wherein the difference frequency is obtained by an independent local oscillation generator whose frequency is entirely independent of the received or re-transmitted waves.

Figure 1 may be modified by connecting the input to divider 10, namely, line 8, to transmission line 44 choosing an appropriate division factor for the dividing apparatus. In this case, however, the constancy of the divider output would depend upon the constancy of the output in the output circuit of converter 32.

As illustrated in Figure 1, the dividing factor of divider 10 is seen to be 1000. Hence, the output in line 28 will not be a wave of constant frequency, but will be a wave of .5 mc. plus and minus 200 cycles, assuming a maximum deviation of plus and minus .2 mc. in the received waves. This variation in frequency in line 28 may increase or decrease the resultant modulation at retransmitting antenna 42 by plus and minus 200 cycles, but since this is a very small amount relative to the signal modulation of plus and minus .2 megacycles it may be disregarded or neglected for all practical purposes.

The frequency dividers 10 may be of the type described in, and follow the principles of frequency division of, the patents to M. G. Crosby Nos. 2,230,231 and 2,230,232. This is not only true of the divider 10 of Figure 1, but is also true of the frequency dividers used in the other forms of my present invention about to be described, or, the dividers may follow the circuits and principles laid down by G. L. Beers in his U. S. Patent 2,356,201 dated August 22, 1944.

In the radio relaying system of Figure 2 assume, for example, the received wave picked up by antenna 206 has a mean frequency of 1000 megacycles and carries a maximum frequency swing of plus and minus .2 mc. The received waves are fed through line 292 to amplifier 204. Part of the amplified waves are fed through line 206 to frequency dividers, amplifiers and filters 208 so that the mean frequency of the output thereof in line 210 is one megacycle. This one megacycle output is fed to a converter 212 which is also supplied with waves having a mean frequency of .1 mc. through line 214. The wave energy in line 214 is derived from the signal and, more specifically, from amplifier 204 through line 216 and frequency dividers 218, 220 which may also include amplifying stages.

By the action of converter and filter 212, a wave of mean frequency of 1.1 mc. is filtered out in line 222 which is fed into converter, filter and amplifier 224. Converter 224 is also fed with a wave having a mean frequency of 500 mc. derived from divider 218. The 500 mc. wave is fed through line 226 to the converter 224. As a result of the converting and filtering action in 224 a wave of mean frequency of 501.1 mc. appears in line 228 which may then be multiplied in frequency multiplier 230 to 1002.2 megacycles, amplified in amplifier 232 and radiated by way of radiating antenna 234.

If desired in the modification of Figure 2, converter and filter 212 may be designed to feed 0.9 mc. into line 222 and the filter 224 may be de-

signed to feed into line 228 498.9 mc. or in case 0.9 mc. is used in line 222, filter 224 may be arranged to pass either a wave having a mean frequency of 499.1 mc. or 500.9 mc. The frequency multiplier 230 may have a multiplying factor of two or any higher whole number, as desired. Assuming a multiplying factor of two so that the frequency multiplier acts as a doubler, then, depending upon the input to multiplier 230, the mean frequency of the wave radiated by antenna 234 will be 997.8 megacycles or 1002.2 megacycles or 998.2 megacycles or 1001.8 megacycles.

In Figure 3, assume that a frequency modulated wave having a mean or carrier frequency of 60 mc. is received upon the receiving antenna 300. The received wave is amplified in amplifier 302 and fed to a converter or carrier suppression modulator 304 which is also supplied with waves having a mean frequency of .6 mc. through line 306. The wave energy in line 306 is derived from the received signal by means of the frequency dividers 308 and filters and amplifiers 310. Of the resulting side bands following from the action of converter 304 either the upper side band having a mean frequency of 59.4 mc. may be selected by filter and amplifier 312 or the lower side band having a mean frequency of 60.6 mc. The selected side band is fed through a transmission line 314 to amplifier 316 and then radiated by transmitting antenna 318.

In the system of Figure 3, amplifier 316 may include a frequency multiplier, such as a doubler, in which case the radiated frequency will have a mean frequency of twice that appearing in line 314.

It is to be noted that in both Figures 2 and 3, the retransmitted wave must bear a fixed relationship to the received wave since all changes in frequency are derived from the received wave and are totally independent of any local oscillation generator freely operating at its own frequency.

The relay system of Figure 4 is somewhat similar to that shown in Figure 2. The wave frequencies marked upon Figure 4 are given by way of example and obviously other values may be chosen. It may be assumed that the incoming wave has a mean frequency of 600 megacycles and that the maximum deviation in frequency produced by the strongest modulating signal is plus and minus 50 megacycles. The wave frequencies marked on Figure 4 indicate only the mean frequencies and do not show the effects of division and multiplication on the deviations which may readily be calculated from the values shown.

More specifically, in Figure 4 waves received upon antenna 400 are amplified at amplifier 402. Part of the amplified waves is divided in frequency dividers 404 and fed to a converter or heterodyning detector or modulator 406. A heterodyning wave is also fed to the converter 406 through line 408 fed by dividers 410, 412 and 414, in turn energized by wave energy from amplifier 402 fed to the input of divider 410 through line 416. Filter 410 selects either the upper or lower side band of frequencies produced by converter 406 and the selected band of frequencies is fed to frequency multipliers, amplifier and filter 420, in turn energizing re-transmitting antenna 422.

Also in Figure 4 it is to be noted that all freely oscillating oscillators have been eliminated, as a consequence of which the re-transmitted wave at 422 always bears a definite, fixed relation to the frequency of the input wave received upon receiving antenna 400.

The frequency dividers in any of the modifica-

tions described hereinabove may be made in accordance with the principles set forth in the patents to M. G. Crosby Nos. 2,230,231 and 2,230,232 or in the copending application of G. L. Beers, Serial No. 430,588, filed February 12, 1942, now U. S. Patent 2,356,201. The frequency multipliers referred to hereinabove may be set up in accordance with the principles set forth in the patent to C. W. Hansell No. 1,878,303. The reactance tube frequency control circuit may follow the principles set forth in the patents to M. G. Crosby Nos. 2,279,659, 2,279,660 and 2,279,661. Amplitude limiting may not only be used in the final amplifier stages, but may also be used in the intermediate frequency amplifiers and in the initial amplifiers connected to the receiving antennas as well.

Also, it is to be noted where frequency dividers are employed, the succeeding filters need not have a pass band wide enough to pass the input to the divider. For example, in Figure 2 divider 208 divides down not only the mean frequency received on antenna 202, but also the deviation. This means that the filters in the output of 208 need be designed to pass only a band of frequencies substantially narrower than that received upon the antenna 200.

Having thus described my invention, what I claim is:

1. The method of wave conversion which includes heterodyning waves, the frequency of which is to be changed, to an intermediate frequency, frequency dividing wave energy derived from said waves, combining the frequency divided wave energy and the waves of intermediate frequency and utilizing the resultant wave energy.

2. The method of converting waves to another frequency which includes heterodyning a part of the waves to be converted to an intermediate frequency, frequency dividing another part of the waves to be converted to a lower frequency, combining the waves of intermediate frequency and the waves resulting from the division, selecting a portion of the combined waves and heterodyning the selected portion to a desired frequency.

3. In a radio relay system, means for receiving angular velocity modulated waves, a frequency divider for frequency dividing a part of the received waves, a source of heterodyning oscillations, apparatus for combining said heterodyning oscillations and another part of the received waves to produce an intermediate frequency, means for heterodyning the frequency divided waves and the waves of intermediate frequency, and means for utilizing the last-mentioned heterodyned waves.

4. In a radio relaying system, means for receiving angular velocity modulated waves, a source of heterodyning oscillations, means to heterodyne a part of the received waves with waves from said source so as to produce an intermediate frequency, a frequency divider for frequency dividing another part of the received waves, means for combining the divided waves and waves of intermediate frequency, means for filtering the combined waves, and means for heterodyning the filtered waves to a higher frequency with waves derived from said source.

5. The method which includes frequency dividing one portion of alternating wave energy, frequency dividing to a greater degree another portion of said alternating wave energy, and combining the divided energies.

6. The method which includes frequency dividing one part of alternating electrical wave

energy, frequency dividing to a greater degree another part of the wave energy, heterodyning the divided energies, filtering the heterodyned energies and utilizing the filtered energies.

7. The method which includes frequency dividing one portion of alternating wave energy, frequency dividing to a greater degree another portion of said wave energy, heterodyning the divided waves, filtering the heterodyned waves and frequency multiplying the filtered waves.

8. Apparatus for relaying angle modulated waves comprising a frequency divider for dividing one portion of the modulated waves, another frequency divider for frequency dividing to a greater degree another portion of the modulated waves, means for heterodyning the frequency divided waves, a filter for filtering the heterodyned waves, and apparatus for utilizing the filtered waves.

9. Apparatus as claimed in claim 8 characterized by the fact that a frequency multiplier is provided for frequency multiplying the filtered waves.

10. The method of wave conversion which includes frequency dividing a portion of electrical waves to be converted, heterodyning the frequency divided waves and another portion of the waves to be converted, filtering the heterodyned waves, frequency multiplying the filtered waves and utilizing the frequency multiplied waves.

11. A radio relaying system comprising means for receiving radio waves, means for frequency dividing one portion of the received waves, means for combining another portion of the received waves with the frequency divided waves, a filter for filtering the combined waves, and a frequency multiplier for frequency multiplying the filtered waves.

12. The method which includes dividing the frequency of one portion of electrical waves and successively heterodyning the frequency divided waves with waves of different frequency resulting from frequency divisions of other portions of said wave energy.

13. The method which includes frequency dividing one portion of electrical wave energy to one frequency, frequency dividing another portion of said electrical wave energy to another frequency, heterodyning the waves of divided frequency, filtering the heterodyned waves and frequency multiplying the filtered waves.

14. In a radio relay system, means for receiving waves, a frequency divided for frequency dividing a part of the received waves, a source of heterodyning oscillations, apparatus for combining said heterodyning oscillations and another part of the received waves to produce an intermediate frequency, means for heterodyning the frequency divided waves and the waves of intermediate frequency, and means for utilizing the last-mentioned heterodyned waves.

15. In a radio relaying system, means for receiving high frequency waves, a source of heterodyning oscillations, means to heterodyne a part of the received waves with waves from said source so as to produce an intermediate frequency, a frequency divider for frequency dividing another part of the received waves, means for combining the divided waves and waves of intermediate frequency, means for filtering the combined waves, and means for heterodyning the filtered waves to a higher frequency with waves derived from said source.

16. A relaying system for relaying phase or frequency modulated waves comprising a source of frequency or phase modulated waves, an amplifier

for amplifying waves from said source, a frequency divider for frequency dividing a portion of the output of said amplifier, a source of substantially constant frequency oscillations, a frequency multiplier for frequency multiplying waves from said source of constant frequency oscillations, a converter for heterodyning together a portion of the output of said multiplier and another portion of the output of said amplifier, apparatus for amplifying and filtering the output of said converter, another converter in which the output of said last-mentioned amplifier and filter and the output of said frequency divider are heterodyned together, an amplifier and filter coupled to the output of said last-mentioned converter, another converter for heterodyning together another portion of the output of said frequency multiplier and the output of said last-mentioned amplifier and filter, and a filter and amplifier for filtering and amplifying the output of said last-mentioned converter.

17. A relaying system for phase or frequency modulated waves comprising an antenna for picking up phase or frequency modulated waves, an amplifier for amplifying the waves so picked up, a frequency divider for dividing a portion of the output of said amplifier, a local oscillation generator, a frequency multiplier for frequency multiplying the output of said generator, apparatus for heterodyning a portion of the output of said frequency multiplier and another portion of the output of said amplifier, apparatus for amplifying and filtering the output of said heterodyning apparatus, combining apparatus for combining the amplified and filtered output of said heterodyning apparatus and the output of said frequency divider, filtering apparatus coupled to the output of said combining apparatus, a converter for heterodyning together the output of said filtering apparatus and another portion of the output of said frequency multiplier, a filter and amplifier coupled to the output of said converter, and a radiating antenna coupled to the output of said filter and amplifier.

18. A relaying system for relaying phase or frequency modulated waves comprising an antenna for receiving modulated phase or frequency modulated waves, an amplifier for amplifying the waves picked up by said antenna, a series of frequency dividers for frequency dividing a portion of the output of said amplifier, a filter coupled to the final divider, a local generator, a frequency multiplier frequency multiplying the output of said local generator, a first converter in which a portion of the output of said frequency multiplier and another portion of the output of said amplifier are heterodyned together, an amplifier and filter for amplifying and filtering the output of said first converter, a second converter in which the filtered output of the first converter and the filtered output of the last of said series of dividers is combined, a filter filtering the output of the second converter, a third converter in which the filtered output of the second converter and another portion of the output of said frequency multiplier are heterodyned together, a filtering system for filtering the output of the third converter, and a radiating antenna coupled to said filtering system.

19. A radio relay system comprising a receiving antenna, an amplifier for amplifying waves received upon said antenna, a frequency divider for frequency dividing the output of said amplifier, apparatus for heterodyning the output of said frequency divider to a higher frequency, and

apparatus utilizing the heterodyned waves of higher frequency for re-transmission.

20. A radio relay system comprising a receiving antenna, an amplifier for amplifying waves received upon said antenna, a frequency divider for frequency dividing the output of said amplifier, apparatus for heterodyning the divided waves to waves of another frequency, apparatus for heterodyning the heterodyned waves to a much higher frequency, a frequency multiplier for frequency multiplying said waves to a much higher frequency, and a radiating antenna for radiating the frequency multiplied waves.

21. A radio relay system comprising an antenna for receiving waves to be relayed, an amplifier coupled to said antenna, a frequency divider for frequency dividing the output of said amplifier, apparatus for successively heterodyning the output of said frequency divider with frequency divided waves also derived from said amplifier but having higher and lower orders of frequency division respectively, filtering and amplifying waves derived from the last heterodyning means, and utilizing the last-mentioned filtered and amplified waves.

22. A radio relay system comprising a receiving antenna, an amplifier coupled to said receiving antenna, a frequency divider for dividing a portion of the output of said amplifier, a first converter to which said frequency divided waves are fed, a frequency dividing system for frequency dividing to a high order of frequency division another portion of the output of said amplifier, means feeding said highly frequency divided energy to said first mentioned converter, apparatus for filtering the output of said converter, a second converter to which said filtered output is fed, apparatus for dividing to a relatively small degree a portion of the output of said amplifier, said output divided to a small degree being fed to said second converter, a second filter for filtering the output of said second converter, a frequency multiplier coupled to the output of said second filter, an amplifier and filter coupled to the output of said frequency multiplier, and a radiating antenna coupled to the output of said amplifier and filter.

23. A radio relay system comprising a receiving antenna, an amplifier for amplifying waves picked up by said antenna, a frequency divider for frequency dividing a portion of the output of said amplifier, a converter in which an undivided portion of said amplifier and said frequency divided portion are combined, a filter and amplifier coupled to the output of said converter, and a radiating antenna coupled to the output of said filter and amplifier.

24. An alternating current system comprising a receiving antenna, an amplifier coupled to said antenna, a frequency divider for frequency dividing a portion of the output of said amplifier, a series of frequency dividers for frequency dividing to a higher degree another portion of the output of said amplifier, a converter in which said divided energies are combined, a filter coupled to the output of said converter, and a utilization circuit coupled to the output circuit of said filter.

25. A relay system for relaying phase or frequency modulated waves comprising a receiving antenna, an amplifier coupled to said antenna, a frequency divider for frequency dividing a portion of the output of said amplifier, a series of frequency dividers for frequency dividing to a higher degree another portion of the output of

said amplifier, a converter in which said divided energies are combined, a filter coupled to the output of said converter, frequency multiplying, amplifying and filtering apparatus coupled to the output of said filter, and a re-radiating antenna coupled to the output of said frequency multiplying, amplifying and filtering apparatus.

26. A radio relay comprising a receiving antenna, a series of frequency dividers for dividing down the frequency of a portion of waves derived from angle modulated waves picked up by said receiving antenna, circuits and apparatus for reducing the mean frequency of another portion of waves derived from angle modulated waves picked up by said receiving antenna, a converter for combining the output of the last divider of said series of frequency dividers and the output of the circuits, and apparatus for reducing the mean frequency of waves derived from waves received on the receiving antenna, a filter and

10

amplifier coupled to the output of said converter for transmitting and amplifying a band of signaling waves, and a retransmitting antenna for transmitting waves derived from waves transmitted by said filter and amplifier.

27. In combination, at a radio relaying station, a receiving antenna, an amplifier for amplifying angle modulated waves received upon said receiving antenna, a series of frequency dividers for frequency dividing a portion of the output of said amplifier, a converter for combining another portion of amplified waves derived from said amplifier with waves derived from an output circuit of said series of dividers, a filter for filtering the output of said converter so as to transmit a band of frequencies, and a transmitting antenna energized by waves derived from waves transmitted by said filter.

HARRY TUNICK.
